FOUNDATION GARMENTS

Marcel Gingras, St. Foy, Quebec, Canada, assignor to
Dominion Corset Company, Limited, Quebec, Quebec,
Canada

Filed Aug. 10, 1962, Ser. No. 216,144
2 Claims. (Cl. 128—523)

This invention relates to foundation garments and has
particular reference to panty-girdle type foundation gar-
ments.

The invention consists essentially in the provision of a
panty-girdle in which the panty legs may be shortened
by cutting through certain sections of the legs and in which
the shortened leg edges remain free from ravelling.

Panty-girdles are manufactured in various sizes and of
specific leg length styles to suit the average type of figure,
but in order to suit the individual requirements of the
wearer it is also necessary to provide a further range of
leg length styles in combination with each of the sizes.
This results in the need to manufacture a very large range
of individual size and style combinations and makes it also
necessary for stores to retain a large inventory to provide
satisfactory customer service.

The main object of this invention is to provide a panty-
girdle in which the panty leg lengths may be shortened
to suit the individual style or taste of the wearer.

Another object is to provide a panty-girdle in which
the legs are so woven that they may be shortened by cut-
ting through certain sections without the need for further
finishing operations to prevent ravelling of the remaining
raw leg edges.

To achieve these objectives, the leg members are man-
ufactured from elastic material woven in circumferentially
extending leg bands which are spaced apart and interwoven
with relatively narrow and circumferentially extending
connecting bands of relatively light weight material. The
leg bands and connecting bands are interwoven to provide
a locked weave at the circumferential edges of the leg
bands. In this way, the panty legs may be shortened by
cutting through any of the narrow connecting bands, with
the locking weave at the circumferential edges of the elas-
tic leg bands thereby preventing ravelling.

In the preferred execution of this invention, the leg
members leave the loom with transverse edges which are
sewn together to form seams at the inside face of the leg.
In order to prevent opening of the seams when the legs
are cut to the required lengths, locking stitches are sewn
across the seams at the lower edges of each of the leg
bands.

The leg members are joined to the lower edges of the
main body of the girdle with a line of overedging seaming
which is opened flat to prevent a smooth finish to the skin
of the wearer.

These and other objects of the invention will be appar-
ent from the following detailed specification and the ac-
companying drawings in which:

FIG. 1 is a substantially front view of a panty-girdle
according to the present invention and

FIG. 2 is an enlarged side view of the leg members,
taken in the direction of arrow 2 in FIG. 1.

With reference now to FIGS. 1 and 2 which show the
preferred execution of the invention, the leg members 10
are attached to the main body 11 of the panty-girdle by

2

overedging seams 12. Leg members 10 are composed of
a plurality of circumferentially extending leg bands 13
made from a woven elastic material stretchable in two
directions, spaced apart and interwoven with a plurality
of relatively, narrow circumferentially extending connect-
ing bands 14 made from a relatively light weight woven
non-elastic material.

The main feature of this invention is that the circum-
ferential edges 15 of leg bands 13 are woven with a lock-
ing weave to provide a non-ravelling edge when leg mem-
bers 10 are shortened by cutting through connecting bands
14.

The transverse edges of each leg member 10 are joined
together with a closing seam 16 and to prevent closing
seam 16 from opening when leg members 10 are short-
ened, locking stitches 17 are sewn over closing seam 16
at the lower edges of each leg band 13.

The main advantage of this invention is that the wearer
can shorten the panty legs to the length best suited to her
individual requirements, simply by cutting through the
connecting bands. The panty legs may also be manufac-
tured of such a length to extend below the knees for secur-
ing a perfect fit under fitted pants. The panty legs can
then be shortened at a later date if so desired, to allow
for wearing the panty-girdle with a gown.

Another advantage of this invention is that manufac-
turing is simplified by limiting the number of combina-
tions of size and leg length styles to nominal basic sizes.

The foregoing specification applies only to the preferred
execution of the invention and it will be understood that
the improved features can apply to other types and styles
of panty-girdles.

What I claim is:

1. A panty girdle including two tubular leg members
open at their lower ends, each of said leg members com-
prising a plurality of leg bands of woven stretchable mate-
rial extending around the entire circumference of the leg
member and a plurality of connecting bands of relatively
light weight woven material interposed between and inter-
woven with said leg bands and co-extensive therewith, the
weave of each leg band being locked at the circumfer-
ential edges thereto to prevent ravelling of said leg bands
when said leg members are shortened by cutting through
said connecting bands, said panty girdle being further
characterized in that the end portions of each leg mem-
ber are sewn together in a seam transverse to said leg
bands and in that the end portions of said leg bands are
also sewn together by locking stitches extending across
said transverse seam, said locking stitches serving to pre-
vent opening of said transverse seam when said leg mem-
bers are shortened by cutting through said connecting
bands.

2. A panty girdle as set forth in claim 1 in which the
locking stitches of the leg bands are located close to the
lower edges of said bands.
